UNITED STATES PATENT OFFICE.

FRED D. BROOKS, OF RICHLFIELD, IDAHO.

CLEANING-ROD FOR GUNS.

1,288,495.

Specification of Letters Patent. Patented Dec. 24, 1918.

Application filed February 9, 1918. Serial No. 216,407.

To all whom it may concern:

Be it known that I, FRED D. BROOKS, a citizen of the United States, residing at Richfield, in the county of Lincoln, State of Idaho, have invented certain new and useful Improvements in Cleaning-Rods for Guns; and I do hereby declare the following to be a full, clear, and exact description of the invention, such as will enable others skilled in the art to which it appertains to make and use the same.

My invention has for its object the provision of an exceedingly simple and efficient means for securing a cleaning patch of cloth to a rod in such manner that the patch is positively secured to the rod when contracted for insertion in the barrel, but may be merely picked off from the rod when opened out for detachment.

It is more particularly my object to establish this ready and positive securement of the cleaning patch to the rod by a simple rotative engagement of the rod and patch to wind the patch about the rod with portions thereof interlocked with the rod to prevent possible accidental displacement.

It is further my object to provide a patch securing means of this nature which will enable the rod to be engaged with a cleaning patch lost within the rifle barrel, whereby such patch may be readily removed from the barrel.

With the above and other objects and advantages in view, the invention resides more particularly in the novel combination, formation and arrangement of parts herein-after described, and pointed out in the appended claims.

In the accompanying drawings:

40 Figure 1 is an elevational view of my improved means for securing a fabric cleaning patch to the end of a cleaning rod.

Fig. 2 is an end view of the attaching means.

45 Fig. 3 is a sectional view taken through the attaching means longitudinally of the rod.

Referring now more particularly to the drawings, 5 designates the work end portion of a cleaning rod, and for the purposes of this invention, said portion may comprise an integral part of the rod, or may be separable therefrom.

To form my improved fabric patch apply-

ing means, the extremity of the rod is provided with series of screw threads 6 extending inwardly a distance substantially equal to the diameter of the rod, although the distance may be varied to a considerable extent. Immediately inwardly of the screw threads 60 the rod is reduced in diameter to form a consequent annular shoulder 7, and the rod portion inwardly of this shoulder is taperingly increased in diameter to the normal diameter of the rod. The end face of the 65 rod is preferably concave, and cut into the peripheral portion of this concave face are a series of spaced notches, which are inclined with respect to the axis of the rod, the consequent tongues 8 defined by these notches 70 being slightly bent outward to form gripping spurs for the fabric.

Taking up now the operation of this attaching means, the end of the rod is placed against the fabric and rotated, the spurs or 75 tongues gripping into the immediately adjacent portions of the fabric, which causes the fabric to fold inwardly on the rod whereby its folds lie in and interlock with the screw threads, and whereby the fabric is constricted about the shoulder 7 to positively fasten the cloth on the rod so long as the cloth is held in contracted position for engagement in the gun barrel. To release the cloth it is merely necessary to open the same 85 up, whereby it will fall away from the rod.

An exceedingly simple means has thus been provided for securing the fabric patch to a cleaning rod in such manner that the patch is securely held upon either pulling or 90 pushing movement of the rod in the gun barrel. Should, however, a patch become detached and lodged in the gun barrel it can be most readily withdrawn by twisting engagement of my improved securing means 95 therewith, which will wing the fabric thereonto and interlock it with the rod end. By reason of the spurs projecting from the end face of the cleaning rod and eccentric to said face, rotation of the rod within the cleaning patch is prevented. Thus, feeding tendency 100 of the patch up the superimposed threads of the rod is prevented and the end of the rod does not tear through the patch and permit the latter to pass upwardly and out of operative position. It will be furthermore noted that while the threads 6 are righthand threads, the spurs 8 progress oppositely.

Therefore rotation may be given the cleaning rod to follow the rifling of a gun barrel that will otherwise screw the cleaner from the patch. Thus loss of the patch is again from another standpoint, provided against.

What is claimed, is:

1. A cleaning rod having a concave end face and a series of notches cut into said face obliquely of the axis of the rod forming consequent tongues, said tongues being bent outward to form fabric gripping spurs and said rod being provided with recessed fabric receiving portions inwardly of said end.
2. A cleaning rod having fabric gripping spurs projecting from one end face eccentric thereto and having threads upwardly from the spurs for receiving folds of fabric thereupon, the spurs serving to prevent continuous screwing movement of the threads through such fabric.
3. A cleaning rod having fabric gripping spurs projecting from one end face eccentric thereto and having screwthreads upwardly of said spurs for receiving folds of fabric thereupon, the spurs each progressing from

its base to its point angularly of the cleaning rod and oppositely to said threads.

4. A cleaning rod having fabric gripping spurs projecting from its end face eccentric thereto and progressing from their bases to their points, angularly of the rod, the spurs each progressing from its base to its point angularly of the cleaning rod and oppositely to the threads.

5. A cleaning rod having fabric gripping spurs projecting from one end face eccentric thereto and having threads upwardly from the spurs for receiving folds of fabric thereupon, the spurs serving to prevent continuous screwing movement of the threads through such fabric, the spurs each progressing from its base to its point angularly of the cleaning rod and oppositely to the threads.

In testimony whereof, I affix my signature, in the presence of two witnesses.

FRED D. BROOKS.
